W. K. RANKIN

ELECTRIC SWITCH

Filed Aug. 30, 1926

Inventor
William K. Rankin,
by *Wm. K. Rankin*,
His Attorney.

UNITED STATES PATENT OFFICE.

WILLIAM K. RANKIN, OF SCOTIA, NEW YORK, ASSIGNOR TO GENERAL ELECTRIC COMPANY, A CORPORATION OF NEW YORK.

ELECTRIC SWITCH.

Application filed August 30, 1926. Serial No. 132,425.

- My invention relates to electric switches, particularly of the type adapted for the control of high potential large capacity circuits. An object of my invention is the provision of an improved switch of this character which shall be capable of interrupting heavy overload or short circuit currents without damage to the apparatus or danger to attendants.
- 10 My invention will be better understood from the following description, taken in connection with the accompanying drawing, and its scope will be pointed out in the appended claims.
- 15 In the drawing, Fig. 1 is a vertical sectional view of one form of my invention, and Fig. 2 is an elevation partly in section at right angles to Fig. 1 and drawn to a smaller scale.
- 20 Referring to the drawing, the vessel or tank 1 has a cover 2 and contains the insulating liquid 3. Passing through the cover 2 are the two insulator bushings 4 and 4^a through which extend the conductors 5 and 6 for connection with the switch contacts. The supporting base 8, through which extends the passage 9, supports at one end the interrupting chamber 10 by means of the insulator 11 and insulator clamp 12, the chamber 25 being held down on the insulator by the sleeve 13. In the lower end of the interrupting chamber is mounted the segmental socket contact member 15 which is the fixed contact of the switch and which is adapted to receive the movable contact rod 16. The socket contact member 15 is connected to conductor 6 by means of contact plate 17, and contact rod 16 is connected to conductor 5 by means of contact plate 18 and the segmental contacts 19. Within the chamber 10 is a baffle 20 and supports 21, and in the top of the chamber is a small valve 22 for allowing the escape of gas therefrom and the filling of the chamber with liquid. The contact retainer 24 and rod 16 are insulated from the interrupting chamber 10 by the insulator 25, and the contact rod 16 passes out of the chamber through the stuffing box 26. At its upper end the rod 16 has a portion 27 surrounded by the spring 28 and insulated from the lower portion by the insulator 29. The contact rod 16 is retained in its upper position by the plate 30 thereon engaging the catch 31 mounted in the protective cap 32. The catch may be withdrawn and the contact rod released by means of a handle 33 or by any other suitable manual or automatic reclosing means.
- 30 An important feature of my invention is that the movable contact rod is separated from the fixed contact by the force of insulating liquid directed against it, and the arrangement is such that after separation of the contacts any arc that is drawn therebetween is extinguished by a high pressure stream of liquid which is forced through the fixed socket contact member toward the moving contact rod. As a means of furnishing the necessary liquid pressure, I have shown by way of example a spring actuated pump arranged in the tank 1. The pump cylinder 36 is secured to the base 8 with its bore connecting with the passage 9 and near its upper end has small openings 37 which are uncovered when the piston 38 is in its elevated position. The piston rod 39 extends up through the stuffing box 40 in the cover 2 and terminates in an enlargement 41 which has a cam face 42 for a purpose to be described later. Plate 43 secured by the rods 44 to the base 8 and having an opening through which the piston rod passes serves as an abutment for one end of the heavy coil spring 45 which bears at its other end on the flange 46 of the piston and which is compressed when the piston is raised to the position illustrated. Any suitable means may be employed for raising the piston against the spring, which means may connect with the piston rod through the eye 47. For retaining the piston in its upward position I have shown a latching device comprising the bell crank lever 48 and lever 49 each having a roller 50 engaging the cam face 42 and connected to act in unison by the gear segments 51. The levers are retained in the position illustrated by the toggle mechanism 52 which is shown slightly overset and which is adapted to be thrown into buckled position by the solenoid 53. The latter may be made to respond to any desired electrical condition of the circuit controlled by the switch, as for example a predetermined overload, or it may be manually operated if desired.
- 35 With the switch in closed circuit position, as illustrated, the release of the latching device by a buckling of the toggle 52 allows the spring 45 to drive the piston 38 down 100

with considerable force. The insulating liquid thereby forced into the interrupting chamber and against the end of the contact rod 16 drives the rod upward out of engagement with the socket contact member 15 compressing the closing spring 28. Slight leakage around the contact rod closes the valve 22. At the upper end of its travel, the rod is retained by the latch 31 against reclosing. It will be seen that by this construction the contact rod upon leaving the socket contact is followed by a stream of relatively cool insulating liquid under considerable pressure. Any arc that may be drawn between the contacts is thereby subjected to this high pressure stream of cool insulating liquid and is quickly extinguished. While the switch is held open the piston may be raised to the position shown to compress the actuating spring 45 preparatory to a subsequent closing operation. In this position of the piston the openings 37 in the cylinder are uncovered so that the pressure of gas formed in the chamber 10 is relieved, whereupon the small valve 22 opens and allows the gas in the chamber to escape and the chamber to refill with liquid. If the switch is tripped open by a heavy overload or short circuit, the volume of gas formed in the chamber may produce a greater pressure than the spring actuated pump, in which case the liquid may flow back into the pump cylinder compressing the spring until it escapes through the openings 37. To effect a reclosing of the switch, the latch 31 is withdrawn to allow the spring 28 to force the contact rod 16 down into circuit closing position. In this operation liquid displaced by the rod escapes also through the openings 37.

What I claim as new, and desire to secure by Letters Patent of the United States, is:

1. An electric switch comprising an enclosing vessel adapted to contain an insulating liquid, an interrupting chamber therein having a fixed socket contact member at one end thereof, a cooperating movable contact rod extending through the opposite end thereof, a pump in the vessel in communication with the chamber whereby liquid forced into the chamber separates the contacts and flows through the socket contact member; a spring for operating the pump and load responsive means for releasing the spring. 45

2. An electric switch comprising an enclosing vessel containing insulating liquid, an interrupting chamber therein having a fixed contact, a cooperating contact rod extending into the chamber, a pump immersed in the liquid in said vessel and connected to the chamber at a point opposite the end of the contact rod, and energy storing means for actuating said pump. 55

3. An electric switch comprising an enclosing vessel containing insulating liquid, an interrupting chamber immersed in the liquid in said vessel, a fixed contact at one end of the chamber, a cooperating contact slidably mounted in the other end of the chamber, a pump comprising a cylinder immersed in said insulating liquid and having a discharge passage connecting with the chamber opposite the end of the contact rod, a piston in the cylinder, said cylinder having a pressure relief opening therein arranged to be covered by the piston in its initial forward movement, a spring for operating said piston and overload responsive means for releasing the spring. 60 65 70 75

In witness whereof, I have hereunto set my hand this 27th day of August, 1926.

WILLIAM K. RANKIN.
